AUTOMOBILE WHEEL COVER

William M. Brownlie, Dearborn, Mich., assignor to Chrysler Corporation, Highland Park, Mich., a corporation of Delaware

Application November 2, 1959, Serial No. 58,142

Term of patent 7 years

(Cl. D14—30)

Fig. 1 is a front elevational view of an automobile wheel cover, showing my new design;

Fig. 2 is a sectional view taken on the line 2—2 of Fig. 1;

Fig. 3 is a sectional view taken on the line 3—3 of Fig. 4; and

Fig. 4 is a fragmentary perspective view of the automobile wheel cover.

The essential features of my design reside in the portions shown by means of full lines in the drawing.

I claim:

The ornamental design for an automobile wheel cover, substantially as shown and described.
